UNITED STATES PATENT OFFICE.

FREDERIC R. C. BOYD, OF LYNN, MASSACHUSETTS, ASSIGNOR TO GENERAL ELECTRIC COMPANY, A CORPORATION OF NEW YORK.

NOZZLE FOR ELASTIC-FLUID TURBINES.

No. 814,425.

Specification of Letters Patent.

Patented March 6, 1906.

Application filed October 14, 1904. Serial No 228,377.

To all whom it may concern:

Be it known that I, FREDERIC R. C. BOYD, a citizen of the United States, residing at Lynn, county of Essex, State of Massachusetts, have invented certain new and useful Improvements in Nozzles for Elastic-Fluid Turbines, of which the following is a specification.

At the present time the nozzles of a jet-turbine are the most, or one of the most, expensive parts to construct, owing to the amount of work required to form them accurately.

The present invention has for its object to improve the construction of nozzles for elastic-fluid-turbines, first, by decreasing the cost of manufacture; second, by using interchangeable parts, which permit of renewal when necessary, and, third, by confining all of the expansion to one plane, which reduces the tendency of the jet to spread rapidly after leaving the nozzle and also reduces the tendency to the creation of eddies in the nozzle-passage.

In the accompanying drawings, which illustrate an embodiment of my invention, Figure 1 is a view in elevation looking into the receiving ends of the nozzle. Fig. 2 is a sectional view taken at right angles to that of Fig. 1. Fig. 3 is a section taken on line 3 3 of Fig. 1. Fig. 4 is a side view of a nozzle-partition. Fig. 5 is an end view of the same. Fig. 6 is an elevation of one of the partitions on an enlarged scale and assembled in the nozzle-plate, the latter being shown in dotted lines; and Fig. 7 is a detail view showing a more complete structure with controlling-valves.

1 represents the casing of the turbine, having an opening to receive the nozzle-plate 2. The plate is provided with a curved slot 3, conforming to the curvature of the bucket-wheel 4. The slot should be accurately made, as its side walls form the sides of the nozzle-sections. It can with advantage be formed by a radial milling-cutter properly set to give the desired angles. The walls are preferably parallel, but may diverge or converge, as desired. Formed in the side walls of the slot are pairs of grooves 5, there being 50 as many pairs as there are partitions 6. The grooves of each pair are directly opposite and receive the projections or feathers 7 on the partitions. The grooves 5 resemble to a certain extent a screw-thread of coarse pitch.

They may extend from one side of the nozzle-plate to the other, or they may extend only part way. In the latter case the surface of the bowl is unbroken, which is advantageous in that it reduces eddies. The partitions control the expansion of the motive fluid; hence they must be accurately formed. As shown, they taper from one end to the other and conform to the shape of the slot. In manufacturing the partitions in large quantities special machinery is preferably employed; but where they are made in small quantities a milling-machine will be found to be satisfactory to produce the form shown in Fig. 4. The curvature illustrated in Fig. 5 can best be formed on a face-plate, as of a lathe or boring-mill. It is preferable to mount a number of partitions on the machine and form them in a single operation. The large ends of the partitions are curved somewhat, as shown in Fig. 2, to form bowls 8, and the formation of these bowls has an important bearing on the flow of fluid through the nozzle-passages. The partitions in a given nozzle are alike, and being interchangeable new ones can be substituted when the old ones are worn. Further, the expansion ratio between the throat or narrowest part of each nozzle-passage and the discharge end can be changed by substituting partitions having different shapes. For example, the partitions may be of uniform thickness, in which case the nozzle-sections would have no expansion, or the expansion may be greater or less than that shown. It is to be noted that the throat and discharge end of each section are rectangular in form, and the stream of motive fluid is thus effectively delivered to the buckets. In all of the cases specified the projections on the edges of the partitions remain the same.

As has been stated, the walls of the slot in the nozzle-plate are parallel, and the expansion is provided for by the shape of the partitions. This means that the expansion will take place in a circumferential and not in a radial direction, which reduces the tendency of the jet issuing from the several sections to spread radially and also reduces the tendency of the fluid to create eddies.

The partitions instead of being provided with projections which fit into grooves in the nozzle-plate may be held in place by screws, pins, or the like. The use of projections is

preferable, however, since they make a fluid-tight joint between one passage and the next.

The partitions are held in place by a retaining device, which may take the form of a thin plate 9, or they may be held by a ported plate 10, such as shown in Fig. 6. The ported plate may also serve as seats for the separately-actuated valves 11. In the plates are ports 12, that convey fluid to the nozzle-sections. These ports may extend to individual sections, or the sections may be arranged in groups. Surrounding the valves and the admission ends of the nozzles is the valve-chest 13.

In the construction shown in Fig. 2 the end portions of the slot in the nozzle-plate form parts of the end nozzle-sections. This means that they will have to be specially formed, and while this is not difficult, owing to the length of the slot, it takes considerable time. In Fig. 7 is shown an arrangement of parts where the above-mentioned operation is unnecessary. The slot in the nozzle-plate 2 is made slightly longer than before and is provided with extra grooves to receive the end partitions, the said partitions taking the place of the finished ends of the slot in Fig. 2. Between the ends of the slot and the adjacent partitions are filling-blocks 14. So long as they prevent the escape of fluid their construction is immaterial.

In accordance with the provisions of the patent statutes I have described the principle of operation of my invention, together with the apparatus which I now consider to be the best embodiment thereof; but I desire to have it understood that the apparatus shown is only illustrative and that the invention can be carried out by other means.

What I claim as new, and desire to secure by Letters Patent of the United States, is—

1. In a nozzle, the combination of a nozzle-plate containing a slot having concentric

walls, detachable partitions located in the slot for dividing it into passages, and supply-ports for the passages. 45

2. In a nozzle, the combination of a nozzle-plate containing a slot having concentric walls, detachable partitions located in the slot for dividing it into fluid-expanding passages, 50 and a chest inclosing the admission ends of the passages.

3. In a nozzle, the combination of a nozzle-plate containing a slot having concentric walls, detachable partitions located in the slot 55 for dividing it into fluid-expanding passages, projections on the partitions which enter grooves in the slot, and a ported plate for holding the partitions in place through which the motive fluid passes. 60

4. In a nozzle, the combination of a slotted nozzle-plate, partitions located in the slot for dividing it into passages, a ported plate whose ports register with the admission ends of the 65 passages, and a chest which incloses the ported plate.

5. In a nozzle, the combination of a slotted nozzle-plate, partitions located in the slot for dividing it into passages, a ported plate whose ports register with the admission ends of the 70 passages, valves for controlling the passage of fluid to the nozzle-passages, and a chest which incloses the plate and valves.

6. A turbine comprising a bucket-wheel and casing, in combination with a nozzle attached to the casing and comprising a nozzle-plate, a detachable partition which forms passages in the plate, and valves which control the admission of fluid to said passages. 75

In witness whereof I have hereunto set my hand this 12th day of October, 1904.

FREDERIC R. C. BOYD.
